UNITED STATES PATENT OFFICE.

WILLIAM ROGERS, OF HARTFORD, ASSIGNOR TO SIMPSON, HALL, MILLER & CO., OF WALLINGFORD, CONNECTICUT.

DESIGN FOR A HANDLE FOR SPOONS OR FORKS.

SPECIFICATION forming part of Design No. 13,838, dated April 3, 1883.

Application filed March 3, 1883. Term of patent 7 years.

To all whom it may concern:

Be it known that I, WILLIAM ROGERS, a citizen of the United States, residing at Hartford, in the county of Hartford and State of Connecticut, have invented and produced a new and original Design for the Handle of Spoons, Forks, &c., of which the following is a specification, reference being had to the accompanying drawing, forming a part thereof, in which is represented a front view of a spoon having my newly-designed handle.

The invention relates to a design for the handle of spoons, forks, and like articles of table-service; and it consists in the peculiar configuration of the upper part of the handle, in connection with scrolls, rosettes, &c., embossed thereon, and also in a series of transverse corrugations of uniform size upon the handle-stem.

To describe the invention more fully, starting from the body of the article, the stem A of the handle is made with substantially parallel sides, and it is provided about half-way of its length with a series of transverse corrugations, *a*, of uniform size. The stem expands laterally in curves *b*, of about a quarter of a circle, where it joins the upper part, B, of the handle. This part B is nearly elliptic in form and

free of fillets, except adjoining the tip, where there are two scrolls, *c*, surrounding rosettes *d*, and between the scrolls is a sheaf of leaves, *e*, secured by a band, *f*, and above said sheaf is a fillet, *g*, inclosing the upper end, as shown in the accompanying illustration.

What I claim is—

1. The herein-described design for articles of table-service, consisting of a handle the stem A of which has substantially parallel sides, and a series of transverse corrugations, *a*, of uniform size, with the contour of the upper part, B, of the handle of substantially elliptical form, as set forth.

2. The herein-described design, having the contour of the stem A terminating in quarter-circles *b*, the substantially elliptical upper part, *B*, having a plain surface free of fillets except at the tip end, said tip having an ornament composed of two rosettes surrounded by scrolls *c*, and between said scrolls a sheaf consisting of several leaves secured together by a band, substantially as shown and described.

WILLIAM ROGERS.
